UNITED STATES PATENT OFFICE.

MORRIS L. COOPER, OF NEW YORK, N. Y.

GARMENT-WEIGHT.

1,388,802.

Specification of Letters Patent. Patented Aug. 23, 1921.

Application filed April 10, 1920. Serial No. 372,875.

To all whom it may concern:

Be it known that I, MORRIS L. COOPER, a citizen of the Republic of Poland, residing at New York city, in the county of New 5 York and State of New York, have invented new and useful Improvements in Garment-Weights, of which the following is a specification.

The present invention contemplates the 10 production of a garment weight which is simple in construction, durable in use, may be readily and effectively connected in the bottom of a skirt, coat or other similar garment, in such a manner as to adapt the garment at all times to retain its original 15 formation.

With the above and other objects in view, the invention consists in the novel features, details of construction and combination of 20 parts which will hereinafter be more fully set forth, illustrated in the accompanying drawing and pointed out in the appended claim.

Figure 1 is a view showing the bottom 25 portion of the skirt provided with the weights constructed and connected therewith in accordance with the invention;

Fig. 2 is a view similar to Fig. 1 with a portion of the skirt shown in section clearly 30 illustrating the manner of connecting the weights with the skirt; and

Fig. 3 is a detail perspective view of the weight disconnected from the skirt.

Referring more particularly to the accompanying drawing, in which like characters of reference refer to corresponding parts in the several views, 5 denotes my improved weight preferably composed of lead, soft metal or a composition of metals, and comprises a substantially convexed body portion 35 6. This weight is of substantially rectangular form and owing to the convexity of the same, provides the weight with slightly beveled longitudinal edges 7 and transverse edges 8. Heretofore, difficulty has been experienced in attaching garment weights to the bottom portion 9 of a skirt A, therefore, I have provided a skirt weight so designed to enable a quick and firm connection of the

weight with the skirt A. To this end, the 50 beveled longitudinal edges 7 are stamped out to provide therein a pair of spaced longitudinally arranged elongated slots 10 and a pair of special parallel slots 11. The purpose of these slots is to permit of the weights 55 being firmly connected to the inner face of the bottom of the skirt A by stitches 12. The manner of connecting the weight to the garment is further obvious, but the same when in applied position prevents the garment 60 from being presented with a bulged or unsightly appearance and serves to hold the garment at all times in its original position and to prevent the wind from hoisting or lifting the garment. 65

From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device shown is 70 75 merely illustrative and that such changes may be made when desired as are within the scope of the appended claim.

What is claimed as new is:

A garment weight adapted to be connected 80 to the bottom inner facing of a skirt in spaced relation with respect to one another and each comprising a convexed body portion of rectangular form, the material forming the body being reduced in thickness adjacent the edges thereof to provide the same with a pair of beveled longitudinal edges and a pair of transverse edges, each of the said beveled edges of the body portion being cut out to provide the same with oppositely 85 arranged spaced parallel elongated slots adapting the weight to be sewed to the garment along both the longitudinal and transverse edges for the greater portion of the longitudinal and transverse extent of the 90 body. 95

In testimony whereof I affix my signature.

MORRIS L. COOPER.
